HEEL MOUNTING

Donald K. McLennan, Fellows, Calif.

Application August 7, 1944, Serial No. 548,374

1 Claim. (Cl. 36—36)

1

This invention has to do with a heel mounting and has particular reference to a mounting or fastening means for securing rubber heels, or the like, to shoes so that they can be applied and removed at will. It is a general object of the invention to provide a heel fastening or mounting means whereby heels can be readily conveniently renewed from time to time or transferred from one shoe to another, as wear occurs.

It is common to provide men's shoes with rubber heels, the usual practice being to nail the heels to the shoes so that they are, in effect, permanent integral parts thereof. Many persons wear rubber heels irregularly, that is, they will wear them down at one side or at a particular point and such wear simply serves to aggravate the condition or conditions which cause such irregular wear. Further, when rubber heels become worn it is ordinarily necessary to take the shoes to a repair shop in order to remove the old heels and to apply new ones.

It is an object of my present invention to provide a mounting for rubber heels whereby the heels are mounted on or attached to the shoes so that the user can readily remove or apply them at will. With the detachable mounting or fastening means provided by the present invention the user can from time to time change the heels from one shoe to another, for instance, he can transpose the heel from the left shoe to the right shoe and the heel from the right shoe to the left shoe, with the result that the excessive wear in any particular part is avoided and the life of the heels is extended and the comfort to the wearer is increased.

Another object of my invention is to provide a fastening means of the general character hereinabove referred to which is extremely simple and inexpensive of manufacture. The present invention provides a fastening means involving few simple parts that can be made at little cost and which can be applied to shoes and heels without appreciably adding to their cost.

Another object of the invention is to provide a fastening means of the general character referred to which is completely concealed from ordinary view so that the finished or fully equipped shoes do not vary in appearance from ordinary shoes. The fastening devices of the present invention are of such character and are so located as to be concealed or inconspicuous with the result that they in no way mar or disfigure the shoes.

The various objects and features of my invention will be fully appreciated from the fol-

2

lowing detailed description of typical preferred forms and applications of my invention, throughout which description reference is made to the accompanying drawings, in which:

5 Fig. 1 is a bottom plan view of the heel portion of the shoe showing a rubber heel mounted thereon by means of the fasteners of the present invention. Fig. 2 is a longitudinal vertical sectional view through the heel portion of the shoe 10 and taken through one of the fasteners of the present invention. Fig. 3 is an enlarged detailed 15 sectional view of the several parts of the fastener provided by the invention showing the parts detached or separated one from the other to facilitate illustration. Fig. 4 is a view similar to Fig. 2 showing another form of construction that can be used in carrying out the invention. Fig. 5 is a detailed sectional view taken as indicated by line 5—5 on Fig. 4. Fig. 6 is a view similar to 20 Fig. 5 showing another form of construction that can be employed.

The device or fastener provided by this invention is designed primarily for mounting a heel on a shoe in order that the heel may be removed 25 when desired for replacement or for transfer from one shoe to another. In carrying out the invention I provide a number of units or fasteners embodying the invention and these several units may, in any particular case, be alike. For simplicity of description I will refer to one fastener 30 in detail, it being understood that several fasteners involved in mounting a single heel may be all alike.

The invention may be employed in mounting a 35 heel of any desired material or composition of material. Since rubber or rubber-like materials are commonly used for heels, I will refer to the heels as rubber heels but do not thereby limit this invention to any particular material.

40 In Fig. 1 of the drawings I show a heel mounted by means of a plurality of fasteners A embodying the present invention, the several fasteners being shown in a typical arrangement that may be used in practice.

45 The fastener of the present invention shown in Figs. 1 to 3 of the drawings involves, generally, two members 10 and 11, one attached to the shoe S and the other to the heel H, and means 12 releasably joining the two elements 10 and 11.

50 In the drawings I have indicated, in a general way, a typical shoe construction involving an upper 13, a sole 14 and a portion of a heel 15. The several shoe parts just referred to may be formed of leather, composition or other suitable 55 material employed in shoe construction, and are

secured together or joined to form a single, integral structure. The heel part 15, which is a permanent part of the shoe, is, in effect, a relatively thin heel foundation to which the rubber heel H is applied.

The rubber heel H may be of the general type usually employed on men's shoe. For instance it may be a body of rubber or rubber-like material with its bottom or tread portion fastened to be skid-proof or to have various characteristics desirable in such devices. In accordance with the invention the heel H is formed as an entirely separate or independent unit and is designed to be attached or secured to the shoe S entirely by means of the fasteners A.

The element 10 of the fastener A is fixed to or permanently incorporated in the shoe construction. In the particular case illustrated the element 10 involves a tubular body 20 and a mounting flange 21. The body 20 extends through an opening 22 formed vertically through the shoe structure. In the particular case illustrated the mounting flange 21 is formed at the upper end of the tubular body 20 and is arranged to occur immediately below the inner sole 23 of the shoe construction. The flange 21 serves as a means for effectively securing the member 10 in place, it being understood, of course, that a suitable cement or adhesive may be employed to make the member 10 tight in the opening 22, if desired. The tubular member 20 is arranged and proportioned in the shoe S so that it opens downwardly in the face to which the rubber heel H is to be applied.

The member 11 is carried by the heel H and in the form of the invention being described it involves, generally, a pin 30 and a mounting plate 31. The mounting plate 31 is preferably in the form of a washer embedded at a suitable point in the heel H and the pin extends through the washer and projects from the upper side of the heel to extend into the tubular body 20. In accordance with the invention an opening 32 extends through the heel H in register with the body of element 10 and the washer 31 is embedded in the heel H concentric with the opening 32.

The fastening means provided for joining the elements 10 and 11 involves a threaded connection and a means for locking such threaded connection against release. In the construction being described the threaded connection includes a thread 40 on the pin 30 and a corresponding or complementary thread 41 in the body 20 of element 10. In this case the pin 30 is provided with a head 42 or, in other words, is in the form of a screw and in its working position extends through the washer 31 and is threaded into the socket or opening in the member 20. The head 42 is shaped to receive an operating device so the pin can be readily rotated. In the case illustrated I have shown an ordinary screw driver notch 42a provided in the head 42 making it possible to operate the pin 40 by means of a screw driver.

It is desirable in practice to provide means to prevent disengagement or release of the threaded connection. In the arrangement illustrated a lock washer 44 is provided to be clamped between the head 42 of the pin 40 and the washer 31 when the pin is made tight in the body 20. I prefer to embed the lock washer 44 in the heel along with or adjacent the washer 31 so that it, in effect, becomes a permanent part of the heel.

With the general arrangement above described the pin 40 may be detached from the other parts.

When the construction that I have just described is in use the pin 40 is arranged through the lock washer 44 and the mounting washer 31 and is threaded into the body 20 which is fixed to the shoe S. The pin is tightened into the body 20 so that the head 41 bears tightly on or is frictionally locked by the lock washer 44. When it is desired to remove the heel H from the shoe either to renew it or to change it from one shoe to another, the pins 40 of the several fasteners A can be released or disengaged by unscrewing them from the bodies 20 which are fixed to the shoe S.

In the form of the invention shown in Figs. 4 and 5 the fastening elements 10a and 11a carries by the shoe and the heel respectively are somewhat different in form from the elements above described, and the means 12a is in the form of a pin connection rather than a screw threaded connection.

The element 10a is in the form of a U-shaped bracket carried in an opening 22a provided in the shoe S so that it has a looped part projecting somewhat below the bottom surface 15a of the heel part 15 of the shoe S. Flanges 21a are provided on the bracket to serve as mounting means corresponding to the flange 21 hereinabove described. The element 11a is in the form of a U-shaped bracket carried by the heel H. In this case the U-shaped bracket 11a has flanges 31a embedded in the heel H while the looped portion of the bracket projects into a cavity in the upper side of the heel H, which cavity is extended at 32a to receive the looped part of the bracket 10a. The parts are arranged and proportioned so that when the heel is in place on the shoe the looped portions of the brackets 10a and 11a are in side by side relation or register one with the other, as shown in the drawings.

The fastening means 12a in this form of the invention involves a pin 60 which slidably passes through an opening 61 provided in one of the parts, preferably in the heel H, which opening 61 registers with the registering parts of the brackets so the pin can be readily passed through the opening 61 to pass through the brackets and thus connect them. In the preferred arrangement a hump 62, or the like, is provided on the pin 60 to retard its movement through the brackets and the opening 61 and thus serve as a means for retaining the pin against displacement. In this form of the invention there are no openings in the heel open at the bottom thereof but rather only small openings at the sides to pass the pins 60 which, in practice, may be small elements in the form of wires.

In using the form of the invention shown in Figs. 4 and 5 the pins 60, which may vary in number according to the number and arrangement of cooperating brackets, are arranged in place as shown in the drawings, that is, they are arranged in the opening 61 to extend through the looped parts of the brackets 10a and 11a. The parts are preferably arranged and proportioned so that a suitable amount of pressure is required in order to insert the pins into place. Whenever it is desired to remove the heel either to renew it or to remove it to another shoe, the pins are removed or pushed from position, thus leaving the brackets free to be separated.

In the form of construction shown in Fig. 6 there are two elements 11a at each point of connection or fastening. The elements 11a are spaced apart to receive an element 10a between them and a short pin 60a engages the elements 10a and 11a. The pin 60a is shown as a cotter key with the

usual head at its outer end and with a bent retaining part 62^a at its inner end. It is to be noted that the heel is recessed to receive the key and that the key is completely confined in the recess when in operating position so no parts project from the exterior of the heel.

Having described only typical preferred forms and applications of my invention, I do not wish to be limited or restricted to the specific details herein set forth, but wish to reserve to myself any variations or modifications that may appear to those skilled in the art and fall within the scope of the following claim:

Having described my invention, I claim:

In combination, a shoe, a U-shaped bracket attached to the shoe to project from the heel portion thereof, a heel having an opening, a U-shaped bracket carried by the heel to register with the other bracket when the heel is in place on the shoe, and a pin carried entirely within the opening and engaging the brackets to secure them together, the brackets being disposed so the pin extends transversely of the heel when in operating position.

DONALD K. MCLENNAN. 25
